Primary Examiner — Marianne Pandozzi(57) **CLAIM**

We claim the ornamental design for a vacuum coffee maker, as shown.

DESCRIPTION

FIG. 1 is a front perspective view of a vacuum coffee maker showing our new design;

FIG. 2 is a rear perspective view of the vacuum coffee maker of FIG. 1;

FIG. 3 is a first side elevational view of the vacuum coffee maker of FIG. 1;

FIG. 4 is a second side elevational view of the vacuum coffee maker of FIG. 1;

FIG. 5 is a front elevational view of the vacuum coffee maker of FIG. 1;

FIG. 6 is a rear elevational view of the vacuum coffee maker of FIG. 1;

FIG. 7 is a top plan view of the vacuum coffee maker of FIG. 1; and,

FIG. 8 is a bottom plan view of the vacuum coffee maker of FIG. 1.

The broken lines depict portions of the vacuum coffee maker that form no part of the claimed design.
